UNITED STATES PATENT OFFICE.

EUGÈNE SCHNEIDER, OF LE CREUZOT, FRANCE.

PERCUSSION-FUSE FOR PROJECTILES.

1,232,853.

Specification of Letters Patent. Patented July 10, 1917.

Application filed February 11, 1916. Serial No. 77,712.

To all whom it may concern:

Be it known that I, EUGÈNE SCHNEIDER, a citizen of the Republic of France, residing at Le Creuzot, France, have invented a new 5 and useful Improvement in or Relating to Percussion-Fuses for Projectiles, which is fully set forth in the following specification.

This invention has for its object to provide an improved percussion fuse of the known type which comprises a safety stop or locking device (for enabling the fuse to be transported and handled without danger) which is adapted to be rendered inoperative by the action of the centrifugal force set up 10 by the discharge of the projectile, in combination with a spring-pressed ring or sleeve serving at that time to keep the safety stops in their inoperative position, so as to prevent their untimely return into their safety 15 or operative position. A fuse of this type is described in English Patent No. 28306/08 of 28th December 1908, English Patent No. 22287/10 of 26th September 1910, and the certificate of addition No. 4698/11 of 24th 20 February 1911 to the said patent, describe a fuse of the same type comprising an additional spring-pressed ring or sleeve for preventing the safety stops from becoming inoperative during the whole period of acceleration of the projectile.

In all the known fuses of this type, the safety stops are arranged to operate by direct contact with the movable fuse member which it is desired to prevent from moving. 25 The result is that at the moment when centrifugal force commences to move the safety stops apart, a simultaneous motion of the safety stops and of the movable fuse member takes place owing to the contact and friction between those parts. Consequently, 30 the movable fuse member instead of remaining perfectly stationary by reason of its inertia, is liable to be moved prematurely forward and thus injuriously affect the sensitivity of the fuse.

The present invention has now for its object to avoid that drawback.

For this purpose the movable fuse member and the spring-pressed ring or sleeve 35 which, after the moving apart of the safety stops, prevents their return into their safety or operative position, are constructed in such a manner that the said ring or sleeve constantly separates the safety stops from 45 the movable fuse member, both in the safety

or operative position as well as in the inoperative position of the stops.

A constructional form of this invention is illustrated by way of example in the accompanying drawings applied to a fuse for use 60 in the nose of a projectile.

In these drawings:—

Figure 1 is a longitudinal section of the improved fuse showing the parts in the positions they occupy before the discharge of 65 the projectile.

Fig. 2 is a similar section showing the parts in the positions they occupy when the projectile has left the gun.

As shown, A is a part of the body of the 70 fuse which forms the mounting for the percussion mechanism, and which comprises in the usual manner a fixed fuse member (for instance the striker B) and a movable fuse member C (carrying the percussion cap 75 D). It is to be understood that the reverse arrangement might be employed, that is to say, the movable fuse member may carry the striker, while the fixed member will then carry the percussion cap. 80

According to the present invention the safety stops or locking means which consist of segments E, and which are kept in their inner position or close together in the usual manner by a spring e, instead of maintaining the movable fuse member C stationary 85 by direct contact with the longitudinal wall of the said member C, act against a spring-pressed sleeve or ring F—G which is intended to prevent their untimely return into 90 their operative or safety position.

The ring F which is suitably extended toward the rear, is formed on its outside at its rear end with a cylindrical shoulder f, the rear end surface f¹ of which when at 95 rest, acts to hold back the movable fuse member which for this purpose is provided at its rear with a flange or collar c. The spring G of the ring bears at one end against this ring, and at its other end against the 100 movable fuse member C. The segment stops E are held, in the rest position, between the shoulder a formed on the sleeve A, and the front end surface f² of the shoulder f formed on the ring F. 105

A suitable amount of play is provided between the movable fuse member C and the ring F in order that the latter, while keeping the movable fuse member stationary by means of its shoulder f, which is itself held 110

back by the stops E, shall not exert any pressure upon the longitudinal sides of the movable fuse member.

The fuse may comprise the usual spring-pressed ring (H—I) which serves to hold back the stops E during the acceleration of the projectile.

The operation of the improved fuse is as follows:—

On the discharge of the projectile, the ring H compresses its return spring I, and moves down into the chamber J, and prevents the stops E from being moved apart by the action of centrifugal force. When the acceleration of the projectile has terminated, the spring I returns the ring H forward, whereupon the stops E can move apart and take up the positions shown in Fig. 2, this movement taking place without affecting the movable fuse member C which is not in contact at any point with the said stops.

When the stops have moved apart, the ring F is moved forward by the spring G until the end surface f^2 of its shoulder f has come against the shoulder a of the fuse body. In this position of the spring-pressed ring F—G, the stops E are held stationary and cannot move together again untimely, while the movable fuse member C which has retained its initial position (which leaves to the fuse its entire sensitiveness) has become free to be moved forward by the operation of the mechanism when the projectile strikes an obstacle; in this movement it will be guided by the ring F.

Having now described my invention, what I claim as new and desire to secure by Letters Patent is:—

1. In a percussion mechanism for projectiles, a movable fuse-member, a spring-pressed sleeve loosely surrounding and normally restraining said member, and centrifugally-released locking means coaxial with said sleeve and engaging said sleeve to prevent movement of said sleeve and member, and means to prevent release of said locking means during acceleration of the projectile.

2. In a percussion mechanism for projectiles, a movable fuse-member, a spring-pressed sleeve loosely surrounding and normally restraining said member, centrifugally-released locking means coaxial with said sleeve and engaging said sleeve to prevent movement of said sleeve and member and means normally held out of engagement with said locking means and adapted to engage the locking means to prevent release of the latter during acceleration of the projectile, and means on said sleeve to maintain said locking means in unlocked position upon movement thereof to such position.

3. In a percussion mechanism for projectiles, a movable fuse-member, a spring-pressed sleeve surrounding and normally re-

straining said member, centrifugally-released locking means engaging said member, and means to prevent release of said locking means during acceleration of the projectile.

4. In a percussion mechanism for projectiles, a movable fuse-member, a spring-pressed sleeve surrounding and normally restraining said member, centrifugally-released locking means engaging said member, means to prevent release of said locking means during acceleration of the projectile, and means on said sleeve to maintain said locking means in unlocked position upon movement thereof to such position.

5. In a percussion mechanism for projectiles, a movable fuse-member provided with a flange, a spring-pressed sleeve loosely surrounding said member and normally engaging said flange, and centrifugally-released locking means coaxial with said sleeve and engaging said sleeve to prevent movement of said sleeve and member and means yieldingly held out of engagement with said locking means and adapted to engage the locking means to prevent release of the latter during acceleration of the projectile.

6. In a percussion mechanism for projectiles, a movable fuse-member, a sleeve loosely surrounding and normally restraining said member, a spring tending to move said sleeve to a position releasing said member, and centrifugally-released locking means coaxial with said sleeve and engaging said sleeve to prevent movement thereof under the influence of said spring and means yieldingly held out of engagement with said locking means and adapted to engage the locking means to prevent release of the latter during acceleration of the projectile.

7. In a percussion mechanism for projectiles, a movable fuse-member provided with a flange, a spring-pressed sleeve loosely surrounding said member and normally engaging said flange, centrifugally-released locking means coaxial with said sleeve and engaging said sleeve to prevent movement of said sleeve and member, a second sleeve yieldingly held out of engagement with said locking means and adapted to engage the locking means to prevent its release during acceleration of the projectile and means on said sleeve to maintain said locking means in unlocked position upon movement thereof to such position.

8. In a percussion mechanism for projectiles, a movable fuse-member, a sleeve loosely surrounding and normally restraining said member, a spring tending to move said sleeve to a position releasing said member, centrifugally-released locking means coaxial with said sleeve and engaging said sleeve to prevent movement thereof under the influence of said spring, means to prevent release of said locking means during acceleration of the projectile, and means on said sleeve to

maintain said locking means in unlocked position upon release of said sleeve and movement thereof to a position releasing said member.

5. 9. In a percussion mechanism for projectiles, a movable fuse-member, a spring-pressed sleeve surrounding and normally restraining said member, centrifugally-released locking means engaging said sleeve, a 20 second sleeve adapted to engage said locking means during acceleration of the projectile to prevent release of said locking means, and a spring reacting against said second sleeve and adapted to prevent movement thereof 25 when the projectile is not under acceleration.
10. 10. In a percussion mechanism for projectiles

tiles, a stationary member, a movable fuse-member provided with a flange, a spring-pressed sleeve loosely surrounding said fuse-member and normally engaging said flange, and centrifugally-released locking means normally engaging said stationary member and said sleeve to prevent movement of said sleeve and fuse-member and means to prevent release of said locking means during acceleration of the projectile.

In testimony whereof I have signed this specification in the presence of two subscribing witnesses.
